UNITED STATES PATENT OFFICE.

CARL GUSTAF EMIL LARSSON, OF NORTH PLAINFIELD, NEW JERSEY.

LIFT-BRIDGE.

1,124,922.

Specification of Letters Patent. Patented Jan. 12, 1915.

Application filed June 24, 1908. Serial No. 440,138.

To all whom it may concern:

Be it known that I, CARL GUSTAF EMIL LARSSON, of North Plainfield, in the county of Somerset and State of New Jersey, a subject of the King of Sweden, have invented a new and useful Improvement in Lift-Bridges, of which the following is a specification, reference being had to the accompanying drawings, forming part of this specification, in which—

Figure 1 is a side elevation showing the bridge provided with my invention; Fig. 2 is a plan view thereof; Fig. 3 is an elevation showing the bridge in elevated position; Figs. 4 and 5 are views on a larger scale, showing parts of the device, Fig. 4 being a vertical section of an accumulator section and Fig. 5 a vertical transverse section showing the bridge cylinder in end view; Fig. 6 is a side elevation, partly in horizontal section, showing the bridge operating motor applied to the bridge; and Fig. 7 is a plan view, partly in horizontal section, showing the motor.

Referring to the drawings, 2 represents the lift bridge, which may be an ordinary span, supported at one end on horizontal pins 3 so placed that when the span revolves on the axis of the pins 3 it will clear the adjoining structure; and at the other end, when in horizontal position, the span rests upon a support 4. The bridge is adapted to be swung in a vertical plane on the axis 3 from the horizontal position shown in Fig. 1 to the elevated position shown in Fig. 3.

The fixed frame 4 at the end of which the bridge 2 is pivoted, rests at one end against the shoe 3' which carries the pivot 3, and at the other end is fastened to a fixed pier or support 5.

The lifting mechanism of the bridge comprises a cylinder 6, which in the drawings I show pivoted to the frame 4 on horizontal trunnions 7. This cylinder is made telescopic, having one or more internal cylinders 8, 9 and a piston 10, which is connected by pins or trunnions 10' with a connecting or pull member 11 extending to the bridge 2, to which it is connected by a pin 12. The member 11 is also supported on extensions 7' from the trunnions 7 which fit between guideways 13 on the member 11; and the cylinders 6, 8 and 9 also travel on the guideways 13. The cylinders 6 and 9, respectively, are connected to a differential cylinder 14 by pipes 15 and 16, these pipes being

jointed in order to provide for movement; and the cylinders 8 and 9 have stops 17 which limit their motion to the desired extent. The differential cylinder 14 has a piston 18 extending through the end of the cylinder, and it is connected by pipes with an accumulator cylinder or cylinders 19 adapted in the ordinary way for holding the liquid with which the cylinders are operated; and in the case shown in the drawings, where the cylinders are operated by compressed air or gas, it is made strong enough to contain the pressure required for lifting the bridge. The differential cylinder and accumulator may be constructed in various ways, and the differential cylinder is connected with a pump 20 and provided with pipes 21, 22, 23, 24 having suitable valves as shown.

The operation is as follows: Assuming that the bridge is in the position shown in Fig. 1, that the piston 18 in the differential cylinder 14 is near the top of the cylinder, and that the parts of the cylinder 6 and its plunger are as shown in Fig. 6; to open the bridge the valves are closed in the pipes 21 and 23 and are opened in the pipes 22 and 24. This will admit pressure into the cylinder 6 and will force the cylinders 8 and 9 and the plunger 10 outwardly, displacing liquid from the piston-rod end of the cylinder 9 into the upper end of the differential cylinder 14. The motion of the plunger 10, acting through the connecting member 11 will draw the bridge 2 into an upright position.

To close the bridge the pipes 24 and 22 are closed and the pipes 21 and 23 are opened. The pressure is thus taken from the cylinder 6 and the cylinder 9 in front of the piston is put into communication with the lower (power) side of the differential cylinder 14. This, together with the weight of the bridge, will draw the bridge down to a horizontal position, exhausting the fluid through the pipe 15 into the upper (low pressure) end of the differential cylinder 14, and as the area of the top of the piston 18 is greater than the area of its lower side, by reason of the projection of the piston through the end of the cylinder, the piston will be moved thereby and the fluid exhausted by the cylinders 6, 8 and 9 will be forced into the upper end of the differential cylinder. The bridge is thus made to do work in closing by restor-

ing to the accumulator the power expended in lifting the bridge, less the loss due to friction, etc.

The next operation is by means of the pump 20 to pump the fluid from the upper side of the piston 18 to the lower side, so as to force the piston upwardly to the position shown in Fig. 1.

By means of my invention the bridge 2 operates as a simple span when closed, resting upon the supports 3 and 4, and as shown is without any substantial movable counterweight, so that it is raised solely by the action of the cylinders and is lowered mainly by gravity; and when lowered it is useful for work in restoring in part the pressure required to raise it.

The foregoing description presupposes that the member 11 and cylinders 6, 8, 9, and piston rod 10 are made long enough to allow the span 2 to come to a bearing at 4 when the bridge is let down. If, however, these members are shortened some and made strong enough the live load can be carried without a support at 4. On this principle I can build two spans and put them up facing each other when I would get a clear river opening of twice as much as before. The drawings indicate the operating cylinder in the member 11. It can also be placed in either of the members constituting the frame 4.

The bridge is novel in that it dispenses with the necessity for the use of movable

counterweights, and when in closed position is more stable than in the ordinary counterweighted bridge.

By employing a telescopic cylinder I employ the greatest amount of force at the moment when the lifting operation begins and a succeedingly lesser amount of force as the span is lifted. If a non-telescopic cylinder is used, the same amount of force needed at the beginning of the operation would be used at the end of the operation, although a much smaller amount would be required.

I claim as my invention:

1. A lift bridge, a motive cylinder, a pull member in which the cylinder is positioned and which is adapted to be upwardly and rearwardly driven for opening the bridge by the said cylinder, said cylinder being held against rearward movement by a pivotal support.

2. The combination with a pivoted bridge, of a fixed support, a motive cylinder connected to said support, and a pull member connected to the bridge and to the piston of the cylinder, said pull member embracing the cylinder and being movable endwise about the same; substantially as described.

In testimony whereof, I have hereunto set my hand.

C. G. EMIL LARSSON.
